UNITED STATES PATENT OFFICE.

ORVILLE B. SKINNER AND GEORGE M. BACON, OF CLEVELAND, OHIO,
ASSIGNORS OF ONE-THIRD TO GEORGE G. WELLS, OF SAME PLACE.

ELECTRIC-ARC LAMP.

SPECIFICATION forming part of Letters Patent No. 599,480, dated February 22, 1898.

Application filed August 27, 1897. Serial No. 649,680. (No model.)

To all whom it may concern:

Be it known that we, ORVILLE B. SKINNER and GEORGE M. BACON, citizens of the United States, residing at Cleveland, in the county of 5 Cuyahoga and State of Ohio, have invented certain new and useful Improvements in Electric-Arc Lamps; and we do hereby declare the following to be a full, clear, and exact description of the invention, such as will enable others skilled in the art to which it appertains to make and use the same.

Our invention relates to electric-arc lamps. Its object is to increase the efficiency of the lamp; and it consists in the novel features of 15 construction, combination, and correlation of parts, as hereinafter fully described, and specifically pointed out in the claims.

In the drawings, Figure 1 is an elevation, partly in section, of our improved lamp. 20 Figs. 2, 3, and 4 are details showing, on a slightly larger scale, the construction of various parts.

A is the top plate of the lamp. a a are standards thereon, which at their upper ends 25 carry a plate B, on which is placed an electromagnetic coil D, whose pole-pieces d are secured to the plate B and preferably magnetically insulated therefrom, as at d². The holder E for the upper carbon e is tubular 30 and passes through the plates A and B and a guide a², terminating above plate B in an armature f, having at each end an inclined face f², contiguous to a correspondingly-inclined face d³ on the pole-pieces. At the 35 lower part of the holder E is affixed a spring g, which bears upon the carbon through an opening h in the tube E and forces the carbon into good electrical contact with its holder and also retains it firmly in place. A tripping- 40 stop i is affixed to the plate A in such a position that when the holder E descends to a determinable extent the stop will engage the spring g and force it out of contact with the carbon, thereby allowing the carbon to slip 45 downward in the holder.

The bottom plate C is joined to the top plate A by a mica globe k. Surrounding the carbons and interior to the globe k is a cylinder L, of mica, closed at the lower end by a plate 50 l, of conducting material, which carries the holder c for the lower carbon j, and to which

plate the insulated conductor m is electrically connected and through which plate the carbon-holder c passes. The cylinder L is detachably connected to the plate A, preferably by means of the bayonet-lock seen in Figs. 3 and 4. To effect this lock, a rim o, fitting the upper end of the cylinder L, is formed on or affixed to the plate A and provided with one or more pins o², which enter the slots l², 60 Fig. 4, in the metal rim, which preferably forms the upper end of the cylinder L; or the pins o² may be on the rim of cylinder L and the slots l² on the rim o, if preferred. When the cylinder L is in place, the arc is 65 entirely inclosed, the oxygen of the air is practically excluded, and the escape of gases prevented, while the oxidation of the carbons while heated and the deposit of carbon from the gases surrounding the arc are almost entirely avoided.

The positive side of the circuit from the line is connected to the binding-post p, with which one end of the coil D is connected, and after passing through the coil the current 75 passes to the holder E, through the carbons, and by the holder c, plate l, and conductor m to the binding-post p², and thence to the line. In trimming the lamp the carbons are placed in contact, and when current is switched upon 80 the lamp the current energizes coil D and causes its poles d d to attract the armature f, thus lifting the upper carbon out of contact with the lower and establishing the arc. As the carbon wastes the arc finally breaks 85 and the holder E drops, and the spring g is brought in contact with the tripping-stop i, which releases the carbon and allows it to feed down through its holder E into contact with the lower carbon, which closes the circuit again, and the coil D again lifts the holder 90 E and the arc is instantly reformed, and these operations are repeated continuously. A stop s is arranged to limit the upward movement of the armature f to a predetermined 95 extent.

A suitable cap or cover, as t, incloses the parts above plate B and is provided with the usual means of suspension to any insulated holder, or the hook u may be itself insulated 100 from the lamp. An inclosing cover v, as shown in dotted lines, may also inclose the

portions between the plates A and B, and any desired globe of glass may inclose the body of the lamp.

By the construction shown and described we dispense entirely with the usual arm or frame extending down to carry the negative carbon and its connection, which when used creates objectionable shadows, and we render the lamp lighter and the trimming of it quicker, as the cylinder L can be detached entirely by a single motion of the hand without any handling of thumb-screws, &c., as is usually necessary, and can be replaced with equal quickness, thus effecting a considerable saving of time.

What we claim as our invention is—

1. In an arc-lamp the combination of an electromagnet horizontally disposed and having poles with inclined faces, an armature 20 outside the coil and parallel therewith having inclined faces corresponding to those of said magnet-poles, a carbon-holder depending from said armature, a spring retaining the carbon in said holder, a stop limiting the play 25 of said armature, and a trip adapted to release said spring, substantially as described.
2. In an arc-lamp, in combination with a horizontally-disposed electromagnetic coil having pole-pieces with inclined faces, a gravity-acting tubular carbon-holder carrying at 30 its top an armature having inclined faces corresponding to those of said pole-pieces, said holder having a spring attached thereto and bearing on the carbon to retain it in the 35 holder and adapted to be tripped by a fixed stop when the holder descends, to feed down the carbon, substantially as shown and described.
3. In an arc-lamp the combination of an

electromagnetic coil having poles with inclined faces, a carbon-holder having a top piece which forms an armature having correspondingly-inclined faces, a spring affixed to said holder and bearing on the carbon therein, a stop adapted to trip said spring, a 45 mica cylinder attached to the top plate and enclosing the carbons, a conducting-plate closing the bottom of said cylinder, and circuit connections to said coil and to the bottom of said cylinder, substantially as described. 50

4. In an arc-lamp the combination of an electromagnetic coil in circuit in series with the carbons and having pole-pieces with inclined faces, an armature outside of and parallel to said coil and having inclined faces 55 corresponding to those of said poles, a tubular carbon-holder depending from said armature and electrically continuous therewith, a stop adapted to limit the movement of said armature, a spring attached to said holder 60 and bearing on the carbon therein, a rigid stop fixed in the path of said spring and adapted to trip the same, and a mica cylinder carrying the lower carbon and a spring connection for the circuit-wire, said cylinder 65 being air-tight and fitting tightly but detachably upon the top plate, whereby the cylinder may be simultaneously detached from the top plate and the circuit, substantially as described. 70

In testimony whereof we hereto affix our signatures in presence of two witnesses.

ORVILLE B. SKINNER.
GEORGE M. BACON.
